SUBSTITUTED 2-PHENOTHIAZINYL TRIFLUOROMETHYL KETONES

William H. Edgerton, Strafford-Wayne, Pa., assignor to Smith Kline & French Laboratories, Philadelphia, Pa., a corporation of Pennsylvania

No Drawing. Filed May 23, 1958, Ser. No. 737,190

12 Claims. (Cl. 260—243)

This invention relates to novel 10-(dialkylaminoalkyl)-2-phenoxythiazinyl trifluoromethyl ketones useful as therapeutic agents. Further, this invention relates to the novel 2-phenoxythiazinyl trifluoromethyl ketone having utility as an intermediate.

The compounds of this invention are useful, specifically, as tranquilizers, antiemetics, calmatives, antihistaminics and antispasmodics. In addition, these compounds have chemotherapeutic activity, such as antibacterial and fungicidal activity.

The 10-(dialkylaminoalkyl)-2-phenoxythiazinyl trifluoromethyl ketones of this invention are represented by the general formula:

FORMULA I

when A represents a divalent, straight or branched alkylene chain containing 2 to 6 carbon atoms; separating the 2 nitrogens by at least 2 carbons; and R₁ and R₂ represent alkyl or divalent groups which, together with the nitrogen to which they are attached, form a five to six-membered heterocyclic ring, such as pyrrolidinyl, piperidinyl, morpholinyl, thiomorpholinyl, piperazinyl or substituted piperazinyl.

The term substituted piperazinyl is used herein to include moieties such as N-alkylpiperazinyl, N-(ω -hydroxyalkylene)-piperazinyl, N-(ω -alkanoyloxyalkylene)-piperazinyl, N-(ω -benzyloxyalkylene)-piperazinyl, N-(ω -hydroxyalkyleneoxyalkylene)-piperazinyl, N-(ω -alkanoyloxyalkyleneoxyalkylene)-piperazinyl, N-(ω -benzyloxyalkyleneoxyalkylene)-piperazinyl, N-phenylalkylpiperazinyl, N-dialkylaminoalkyleneepiperazinyl, or N-acylpiperazinyl, for example N-alkanoylpiperazinyl or N-benzyloypiperazinyl.

By the term alkyl where used herein, aliphatic groups having not more than 4 carbon atoms and preferably not more than 2 carbon atoms are indicated. The term alkylene, used in connection with a carbon chain, unless stated otherwise represents aliphatic groups of from 2 to 4 carbon atoms and preferably an ethylene group. The term alkanoyl is used to represent an aliphatic acyl group having not more than 4 carbon atoms and, preferably, not more than 2 carbon atoms.

The advantageous compounds of this invention are represented by the following formulas:

FORMULA II

2

when A represents a divalent, straight or branched alkylene chain containing 2 to 4 carbon atoms, separating the nitrogen atoms by at least 2 carbons; and Z represents dimethylamino, piperazinyl, N-alkylpiperazinyl,

5 N-(ω -hydroxyalkylene)-piperazinyl, N-(ω -alkanoyloxyalkylene)-piperazinyl, N-(ω -benzyloxyalkylene)-piperazinyl, N-(ω -hydroxyalkyleneoxyalkylene)-piperazinyl, N-(ω -alkanoyloxyalkyleneoxyalkylene)-piperazinyl or N-(ω -benzyloxyalkyleneoxyalkylene)-piperazinyl.

10 Preferred compounds of this invention are represented by the following formula:

FORMULA III

15 when R represents hydrogen or methyl; and Z represents dimethylamino, N-alkylpiperazinyl, N-(ω -hydroxyethyl)-piperazinyl, N-(ω -acetoxyethyl)-piperazinyl, N-(ω -hydroxyethoxyethyl)-piperazinyl or N-(ω -acetoxyethoxyethyl)-piperazinyl.

20 This invention also includes salts of the above defined bases formed with nontoxic organic and inorganic acids. Such salts are easily prepared by methods known to the art. The base is reacted with either the calculated amount of organic or inorganic acid in aqueous miscible solvent, such as acetone or ethanol, with isolation of the salt by concentration and cooling or an excess of the acid in aqueous immiscible solvent, such as ethyl ether or chloroform, with the desired salt separating directly. Exemplary of such organic salts are those with maleic, fumaric, benzoic, ascorbic, pamoic, succinic, bismethylenesalicylic, methanesulfonic, ethanesulfonic, acetic, propionic, tartaric, salicylic, citric, gluconic, lactic, malic, mandelic, cinnamic, citraconic, aspartic, stearic, palmitic, itaconic, glycolic, p-aminobenzoic, glutamic, benzene sulfonic and theophylline acetic acids as well as with the 8-halotheophyllines, for example, 8-bromotheophylline. Exemplary of such inorganic salts are those with hydrochloric, hydrobromic, sulfuric, sulfamic, phosphoric and nitric acids. Of course these salts also may be prepared by the classical method of decomposition of appropriate salts which is well-known to the art.

25 30 35 40 45 50 55 The novel 2-phenoxythiazinyl trifluoromethyl ketone (Formula IV) is used as an intermediate to prepare the pharmacologically active 10-(dialkylaminoalkyl)-2-phenoxythiazinyl trifluoromethyl ketones represented by Formula I. In general, the preparation is carried out according to the following synthetic procedure:

FORMULA IV

60 65 70 75 Where used herein, the term dialkylaminoalkyl represents aliphatic-aminoalkyl groups, such as dimethylaminoalkyl, and nitrogen-containing heterocyclic-alkyl groups, such as morpholinoalkyl.

75 80 85 90 95 2-phenoxythiazinyl trifluoromethyl ketone, used as an in-

termediate as shown above, is readily prepared by the cyclization of appropriately substituted acetophenones:

X represents chloro, bromo or iodo.

This method is carried out by heating the above acetophenones in the presence of an acid-binding agent, present in an amount sufficient to neutralize the hydrohalic acid formed during the reaction. Exemplary of such acid-binding agents are the alkali carbonates, such as sodium carbonate, sodium bicarbonate or preferably potassium carbonate. The reaction is run in a suitable, nonreactive organic solvent in which the reactants are at least partially soluble. Exemplary of such solvents are dioxane, dimethylaniline, diethylformamide, methylformamide, dimethyl formamide, or dimethylacetamide. Preferably, the solvent is dimethylformamide and other similar lower-carbon amides.

Optimum yields are obtained when catalytic amounts of copper or copper-bronze powder are added, for instance up to 5% by weight of the acetophenone. The reaction mixture is advantageously heated at from about 100 to 220° C. for long periods, such as from 4 to 60 hours. Preferably, the reaction mixture is heated with stirring at the boiling point of the solvent for from 8 to 24 hours. The reaction mixture is worked up by cooling, filtering and quenching in water. The separated product is washed, recrystallized and, optionally, sublimed to give the desired 2-phenothiazinyl trifluoromethyl ketone.

The substituted acetophenones are prepared by methods analogous to those in the prior art. For instance, 4-chloro-3-nitro- α,α,α -trifluoroacetophenone is condensed with o-bromothiophenol under alkaline conditions to give 4-(2'-bromophenylmercapto)-3-nitro- α,α,α -trifluoroacetophenone. The 3-nitro group is reduced with stannous chloride-hydrochloric acid to give 3-amino-4-(2'-bromo-phenylmercapto)- α,α,α -trifluoroacetophenone which is then further reacted as described above.

The 4-halo-3-nitro- α,α,α -trifluoroacetophenones, used as described above, are similarly prepared by methods analogous to those in the prior art. For instance, chlorobenzene is treated with trifluoroacetyl chloride in a typical Friedel-Crafts reaction to give 4-chloro- α,α,α -trifluoroacetophenone which is nitrated with a mixture of nitric acid or potassium nitrate and sulfuric acid to yield the desired compound. Alternatively, 4, α,α,α -tetrachloroacetophenone is converted by means of antimony trifluoride to the α,α,α -trifluoroacetophenone derivative which in turn is nitrated to give 4-chloro-3-nitro- α,α,α -trifluoroacetophenone.

The intermediate 2-phenothiazinyl trifluoromethyl ketone is alkylated with a reactive dialkylaminoalkyl ester to form the novel 10-(dialkylaminoalkyl)-2-phenothiazinyl trifluoromethyl ketones represented by Formula I. Any reactive dialkylaminoalkyl ester may be used, such as halide, preferably chloride or bromide, or an aryl sulfonate, preferably p-toluenesulfonate. The reaction is carried out advantageously by refluxing the reactants in a suitable inert aromatic solvent such as, preferably, benzene, toluene or xylene, in which at least one of the reactants must be soluble. A suitable acid-binding agent is usually included, such as an alkali metal amide, preferably sodium, potassium or lithium amide. Other suitable acid-binding agents are alkali metal hydrides, preferably sodium hydride or alkali metal aryl or alkyl compounds, preferably phenyl or octyl sodium. If an acid addition salt of the reactive dialkylaminoalkyl ester is used, a corresponding increase in the amount of acid-binding agent must be used.

The preferred method of alkylation, however, is to react 2-phenothiazinyl trifluoromethyl ketone with a dialkylaminoalkyl chloride or bromide with slightly less

than one equivalent of sodium or potassium amide in refluxing benzene or toluene for from 30 minutes to 12 hours, preferably one to eight hours.

The 10-(dialkylaminoalkyl)-2-phenothiazinyl trifluoromethyl ketone is preferably isolated by quenching the cooled reaction mixture with water and extracting the separated organic layer with dilute acid, preferably dilute hydrochloric acid. The acid extracts are combined, neutralized carefully with dilute alkali such as sodium bicarbonate and extracted with benzene. The dried benzene extracts are evaporated and the residue fractionally distilled under high vacuum to give the oily base which is conveniently converted into a stable salt by reaction with a suitable organic or inorganic acid.

The 10-(ω -piperazinylalkyl)-2-phenothiazinyl trifluoromethyl ketones are prepared advantageously by alkylating 2-phenothiazinyl trifluoromethyl ketone with an ω -haloalkylpiperazine having the free N-hydrogen of the piperazinyl moiety replaced by an easily removed moiety, for example a carbethoxy or, preferably, formyl group. The N-protective group is then removed under very mild conditions, such as by weakly alkaline hydrolysis. The resulting 10-(ω -piperazinylalkyl)-2-phenothiazinyl trifluoromethyl ketones are then further alkylated to form

modifications corresponding to various substituted piperazinyl moieties as previously defined herein. Such methods of alkylation are by a reactive ester such as an alkyl halide in the presence of an acid-binding agent, as described above, in an inert solvent such as benzene or xylene, or by reaction with an alkylene oxide, such as ethylene oxide in a lower alcohol. In addition, 10-(N-alkyl-N-piperazinylalkyl)-2-phenothiazinyl trifluoromethyl ketones having a terminal group on the N'-alkyl moiety capable of undergoing further reaction, such as ω -hydroxyalkyl, are optionally reacted with an ester such as an acyl halide in the presence of an acid-binding agent to give, for example, N'-acyloxyalkyl derivatives of 10-(ω -piperazinylalkyl)-2-phenothiazinyl trifluoromethyl ketones.

Although 2-phenothiazinyl trifluoromethyl ketone is quite stable, in prolonged contact with aqueous alkali it does have some tendency to undergo a haloform reaction. If this is the case under certain reaction conditions, the keto group can be protected by forming a ketal compound, preferably with ethylene glycol, performing the desired reaction and then removing the protective group by brief treatment with acid.

The foregoing is a general description of the main synthetic routes in the preparation of 10-(dialkylaminoalkyl)-2-phenothiazinyl trifluoromethyl ketone derivatives. It will be readily apparent to one skilled in the art that variations of these procedures are possible. Of particular advantage as a preparative procedure is the method thoroughly discussed above, namely N-alkylation of 2-phenothiazinyl trifluoromethyl ketone in the 10-position of the phenothiazine ring by a reactive dialkylaminoalkyl ester.

It will be readily apparent to one skilled in the art that certain of the compounds of this invention, notably those in which A is represented by an aliphatic carbon chain, branched so that an asymmetric carbon atom is formed, may be present as optical isomers. The connotation of the general formulae presented herein is to include all isomers, particularly the separated d- or l-optical isomers as well as the dl mixture of these isomers. If desired, the isomers may be separated for individual use by separation methods known to the art, such as fractional crystallization, for instance of the d-tartarate salts of the 10-(dialkylaminoalkyl)-2-phenothiazinyl trifluoromethyl ketone derivatives. Alternatively, a synthesis starting with an optically active side chain may yield the desired optical isomer.

The following examples are not limiting but are illustrative of compounds of this invention and the procedures for their preparation and will serve to make fully appar-

ent all of the compounds embraced by the general formula given above and the preparation thereof, respectively.

Example 1

A stirred suspension of 67.5 g. of chlorobenzene and 80.0 g. of aluminum chloride is cooled to -10° C. and 66.3 g. of trifluoroacetyl chloride is added. When the addition is complete, the mixture is allowed to stand at room temperature overnight. The reaction mixture is then poured onto ice and water, and extracted with ether. The dried ether extracts are evaporated to give 4-chloro- α,α,α -trifluoroacetophenone.

A mixture of 31.5 g. of concentrated nitric acid and 49.0 g. of concentrated sulfuric acid, cooled to 0° C., is added slowly to 20.8 g. of 4-chloro- α,α,α -trifluoroacetophenone. The mixture is stirred for three hours at 5° C. and then poured onto ice. The solid is filtered, washed with water and recrystallized to yield 4-chloro-3-nitro- α,α,α -trifluoroacetophenone.

A solution of 25.3 g. of 4-chloro-3-nitro- α,α,α -trifluoroacetophenone in 250 ml. of ethanol is added to a mixture of 4.0 g. of sodium hydroxide in 25 ml. of water and 18.9 g. of o-bromo thiophenol in 300 ml. of ethanol. The suspension is refluxed for one hour and filtered hot. The filtrate yields 4-(2'-bromophenylmercapto)-3-nitro- α,α,α -trifluoroacetophenone upon dilution with a small amount of water and cooling.

A solution of 112.8 g. of stannous chloride crystals in 300 ml. of concentrated hydrochloric acid is carefully mixed with 20.3 g. of 4-(2'-bromophenylmercapto)-3-nitro- α,α,α -trifluoroacetophenone. The mixture is stirred and refluxed for three hours. The cooled reaction mixture is made alkaline, refluxed for 30 minutes and then extracted with benzene. The solvent is removed by distillation in vacuo and upon purification of the residue, 3-amino - 4 - (2' - bromophenylmercapto) - α,α,α - trifluoroacetophenone is obtained.

A suspension of 18.8 g. of 3-amino-4-(2'-bromophenylmercapto) - α,α,α - trifluoroacetophenone, 7.3 g. of anhydrous potassium carbonate and 0.7 g. of copper-bronze powder in 175 ml. of dimethylformamide is heated at reflux with stirring for 15 hours under a stream of nitrogen. The cooled reaction mixture is filtered and the filtrate diluted with water. The solid which thus forms is vacuum sublimed and recrystallized to give pure 2-phenothiazinyl trifluoromethyl ketone.

Example 2

A mixture of 29.5 g. of 2-phenothiazinyl trifluoromethyl ketone (prepared as in Example 1) and 2.2 g. of lithium amide in 100 ml. of dry xylene is refluxed for 15 minutes. A solution of 12.7 g. of 3-chloro-1-dimethylaminopropane in 20 ml. of xylene is then added slowly and the mixture refluxed for three hours. The cooled reaction mixture is treated with water, extracted with dilute hydrochloric acid and the acid extracts neutralized with dilute aqueous sodium bicarbonate. After benzene extraction and subsequent removal of the dried solvent in vacuo, the residue is crude 10-(3'-dimethylaminopropyl) - 2 - phenothiazinyl trifluoromethyl ketone.

Treating an ethereal solution of the free base (1.0 g. in 75 ml. of ether) with ethereal hydrogen chloride yields the hydrochloride salt.

Example 3

A mixture of 29.5 g. of 2-phenothiazinyl trifluoromethyl ketone (made as in Example 1), 3.7 g. of sodium amide and 300 ml. of xylene is refluxed with stirring for 20 minutes. A solution of 18.5 g. of 1-(3'-chloropropyl)-4-methylpiperazine in 100 ml. of xylene is added and the mixture refluxed for four hours. Working up the reaction mixture as described in Example 2, gives the product, 10 - [3' - (4" - methyl - 1" - piperazinyl)-propyl] - 2 - phenothiazinyl trifluoromethyl ketone.

Example 4

A suspension of 14.8 g. of 2-phenothiazinyl trifluoromethyl ketone (prepared as in Example 1) and 1.8 g. of sodium amide in 200 ml. of xylene is heated at reflux with stirring for 20 minutes. A solution of 10.0 g. of 1-formyl-4-(3'-chloropropyl)-piperazine in 30 ml. of xylene is added and refluxing continued for four hours. The reaction mixture is treated with water and the xylene layer extracted with dilute mineral acid. The acid extracts are made basic with dilute sodium bicarbonate solution and extracted with benzene. Evaporation of the solvent in vacuo yields the product, 10-[3'-(N-formylpiperazinyl) - propyl] - 2 - phenothiazinyl trifluoromethyl ketone.

A solution of 89.8 g. of the ketone in 500 ml. of ethanol and 300 ml. of water containing 20 ml. of 40% sodium hydroxide solution is refluxed for 30 minutes. The ethanol is distilled off in vacuo on the steam bath and the residue is treated with benzene and water. The dried benzene layer is evaporated in vacuo to give 10-(3'-piperazinylpropyl) - 2 - phenothiazinyl trifluoromethyl ketone.

Example 5

Ethylene oxide (0.444 g.) is added to a solution of 4.2 g. of 10-(3'-piperazinylpropyl)-2-phenothiazinyl trifluoromethyl ketone (prepared as in Example 4) and the resulting mixture refluxed for two hours. Removal of the solvent in vacuo yields the residual product, 10-[3'-(N-hydroxyethylpiperazinyl)-propyl]-2-phenothiazinyl trifluoromethyl ketone.

A solution of 2.3 g. of this ketone and 0.5 g. of acetyl chloride in 50 ml. of benzene is heated at reflux for 20 minutes and cooled. Evaporation of the solvent in vacuo gives the monohydrochloride salt of 10-[3'-(N-acetoxyethylpiperazinyl)-propyl]-2-phenothiazinyl trifluoromethyl ketone. This is dissolved in alcohol and treated with alcoholic hydrogen chloride. Concentration and cooling yields the dihydrochloride salt.

Similarly, 10-[3'-(N-hydroxyethylpiperazinyl)-propyl]-2-phenothiazinyl trifluoromethyl ketone is reacted in benzene solution with propionyl chloride (0.54 g.) to yield 10-[3'-(N-propionyloxyethylpiperazinyl)-propyl]-2-phenothiazinyl trifluoromethyl ketone hydrochloride.

In the same manner, reaction with benzoyl chloride (0.8 g.) in benzene yields the hydrochloride salt of 10-[3'-(N-benzoyl-oxyethylpiperazinyl)-propyl]-2-phenothiazinyl trifluoromethyl ketone.

Example 6

A suspension of 29.5 g. of 2-phenothiazinyl trifluoromethyl ketone (prepared as in Example 1) and 2.2 g. of lithium amide in 100 ml. of dry xylene is stirred and refluxed for 20 minutes. A solution of 14.2 g. of 1-chloro-3-dimethylamino-2-methylpropane in 30 ml. of xylene is added and the resulting mixture heated at reflux for three hours. The reaction mixture is cooled, treated with water and extracted with dilute hydrochloric acid. The acid extracts are neutralized with dilute sodium bicarbonate solution and extracted with benzene. Removal of the dried solvent gives 10-(3'-dimethylamino-2'-methyl-propyl)-2-phenothiazinyl trifluoromethyl ketone.

The free base (1.0 g.) is dissolved in 100 ml. of ether and treated with an excess of alcoholic hydrogen bromide to separate the hydrobromide salt.

Example 7

A mixture of 14.8 g. of 2-phenothiazinyl trifluoromethyl ketone (made as in Example 1) 1.8 g. of sodium amide and 200 ml. of dry benzene is refluxed for 30 minutes. A solution of 7.8 g. of N-(2-chloroethyl)-morpholine in 25 ml. of benzene is added and the resulting mixture is stirred and refluxed for four hours. The reaction mixture is treated with water and extracted with dilute hydrochloric acid. The extracts are neutralized with dilute

sodium bicarbonate solution and then extracted with benzene. Removal of the dried solvent gives the product, 10-(2'-N-morpholinylethyl)-2-phenothiazinyl trifluoromethyl ketone.

A solution of 1.0 g. of the free base in 100 ml. of ethyl acetate is treated with an excess of alcoholic maleic acid to give the maleate salt upon concentration and cooling.

Example 8

A mixture of 14.8 g. of 2-phenothiazinyl trifluoromethyl ketone (made as in Example 1), 1.8 g. of sodium amide and 10.9 g. of 6-bromo-1-dimethylaminohexane in 100 ml. of dry xylene is heated at reflux for eight hours. Treating the reaction mixture as in Example 2 gives 10-(6'-dimethylaminohexyl)-2-phenothiazinyl trifluoromethyl ketone.

The residue is dissolved in ethyl acetate and reacted with bismethylenesalicylic acid to yield the bis-methylenesalicylate salt.

Example 9

A suspension of 14.8 g. of 2-phenothiazinyl trifluoromethyl ketone (prepared as in Example 1) and 1.8 g. of sodamide in 75 ml. of dry xylene is stirred while a solution of 10.8 g. of 3-bromo-1-piperidylpropane in 100 ml. of xylene is added slowly at 100° C. The mixture is refluxed for three hours, cooled, and treated with water. The separated organic layer is extracted with dilute hydrochloric acid, neutralized with dilute aqueous sodium bicarbonate and further extracted with benzene. Removal of the solvent in vacuo gives 10-(3'-N-piperidylpropyl)-2-phenothiazinyl trifluoromethyl ketone.

Example 10

A stirred suspension of 2.9 g. of 2-phenothiazinyl trifluoromethyl ketone (made as in Example 1) and 0.37 g. of sodamide in 50 ml. of xylene is refluxed while 2.9 g. of 3-bromo-1-pyrrolidinylpropane hydrobromide is added. The resulting mixture is then stirred and refluxed for eight hours. Working up as in Example 2, 10-(3'-N-pyrrolidinylpropyl)-2-phenothiazinyl trifluoromethyl ketone is obtained.

Treating an ethereal solution of the free base with glacial acetic acid furnishes the acetate salt.

Example 11

A mixture of 4.2 g. of 10-(3'-piperazinylpropyl)-2-phenothiazinyl trifluoromethyl ketone (made as in Example 4), 1.6 g. of ω -bromobutanol and 1.5 g. of potassium carbonate in 200 ml. of xylene is stirred and refluxed for five hours. After addition of water to the reaction mixture, the separated xylene layer is extracted with dilute mineral acid. The acid extracts are neutralized with dilute sodium bicarbonate solution and extracted with benzene. Distilling the solvent in vacuo leaves the residual product, 10-[3'-(N- ω -hydroxybutylpiperazinyl)-propyl]-2-phenothiazinyl trifluoromethyl ketone.

A solution of 4.9 g. of this ketone in 75 ml. of benzene is treated with 1.5 g. of butyryl chloride. After standing at room temperature for 12 hours, the reaction mixture is poured into water, neutralized with dilute sodium bicarbonate solution and extracted with benzene. Evaporation of the solvent gives the crude product, 10-[3'-(N- ω -butyryloxybutylpiperazinyl)-propyl]-2-phenothiazinyl trifluoromethyl ketone.

Example 12

A mixture of 14.8 g. of 2-phenothiazinyl trifluoromethyl ketone (made as in Example 1) and 1.8 g. of sodamide in 100 ml. of dry xylene is stirred and refluxed while a solution of 9.4 g. of 3-chloro-1-(N-thiomorpholinyl)-propane in 50 ml. of xylene is added. The resulting mixture is heated at reflux for seven hours. Working up the reaction mixture as outlined in Example 2 results in the isolation of 10-[3'-(N-thiomorpholinyl)-propyl]-2-phenothiazinyl trifluoromethyl ketone.

Example 13

A mixture of 14.8 g. of 2-phenothiazinyl trifluoromethyl ketone (prepared as in Example 1), 1.8 g. of sodamide and 10.0 g. of 3-chloro-2-methyl-1-(N-methylpiperazinyl)-propane in 150 ml. of dry benzene is heated at reflux for six hours. Treating the reaction mixture as described in Example 2 gives 10-[3'-(4'-methyl-1-piperazinyl)-2'-methylpropyl]-2-phenothiazinyl trifluoromethyl ketone. A solution of the free base (1.0 g.) in 100 ml. of ether is treated with an excess of alcoholic hydrogen chloride to give the dihydrochloride salt.

Example 14

A mixture of 14.8 g. of 2-phenothiazinyl trifluoromethyl ketone (made as in Example 1), 1.8 g. of sodamide and 13.2 g. of 3-chloro-1-(N-benzylpiperazinyl)-propane in 150 ml. of toluene is heated at reflux for seven hours. After treating the reaction mixture with water, the separated organic layer is extracted with dilute hydrochloric acid. The acid extracts are neutralized with dilute sodium bicarbonate solution and extracted with benzene. The solvent is removed to give the residual 10-[3'-(N-benzylpiperazinyl)-propyl]-2-phenothiazinyl trifluoromethyl ketone. The free base is reacted with maleic acid in ethyl acetate to furnish the dimaleate salt.

Similarly, by using 15.4 g. of 3-chloro-1-(N- ω -phenylbutylpiperazinyl)-propane, 10-[3'-(N- ω -phenylbutylpiperazinyl)-propyl]-2-phenothiazinyl trifluoromethyl ketone is obtained.

Example 15

To a solution of 4.2 g. of 10-(3'-piperazinylpropyl)-2-phenothiazinyl trifluoromethyl ketone (prepared as in Example 4) in 150 ml. of benzene and 5 ml. of pyridine, 4.0 ml. of acetic anhydride, with swirling. After standing overnight the reaction mixture is washed with water and evaporated. A solution of the residue in alcohol is reacted with one equivalent of hydrochloric acid to yield 10-[3'-(N-acetyl)piperazinyl)-propyl]-2-phenothiazinyl trifluoromethyl ketone hydrochloride.

Example 16

A mixture of 4.2 g. of 10-(3'-piperazinylpropyl)-2-phenothiazinyl trifluoromethyl ketone (made as in Example 4) in 150 ml. of benzene and 2.0 g. of benzoyl chloride is heated at reflux for three hours. Concentrating the reaction mixture yields the solid product, 10-[3'-(N-benzoylpiperazinyl)-propyl]-2-phenothiazinyl trifluoromethyl ketone hydrochloride.

Example 17

A suspension of 4.2 g. of 10-(3'-piperazinylpropyl)-2-phenothiazinyl trifluoromethyl ketone (prepared as in Example 4), 1.8 g. of 2-bromo-2'-hydroxyethyl ether and 1.3 g. of potassium carbonate in 150 ml. of toluene is refluxed for six hours. The reaction mixture is treated with water, the organic layer separated and extracted with dilute hydrochloric acid and neutralized with dilute sodium bicarbonate solution. Extraction with benzene and subsequent evaporation of the solvent yields 10-[3'-(N-hydroxyethoxyethylpiperazinyl)-propyl]-2-phenothiazinyl trifluoromethyl ketone.

Example 18

To a solution of 5.1 g. of 10-[3'-(N-hydroxyethoxyethylpiperazinyl)-propyl]-2-phenothiazinyl trifluoromethyl ketone (made as in Example 17) in 100 ml. of benzene is added 1.0 g. of acetyl chloride and the reaction mixture allowed to stand at room temperature for 24 hours. The reaction mixture is poured into water, neutralized with dilute sodium bicarbonate solution and extracted with benzene. Evaporation of the solvent leaves the crude product, 10-[3'-(N-acetoxyethoxyethylpiperazinyl)-propyl]-2-phenothiazinyl trifluoromethyl ketone. Similarly, acylating with benzoyl chloride (2.0 g.) as

above, 10-[3'-(N-benzyloxyethoxyethylpiperazinyl)-propyl]-2-phenothiazinyl trifluoromethyl ketone is isolated.

Example 19

A stirred suspension of 4.2 g. of 10-(3'-piperazinylpropyl)-2-phenothiazinyl trifluoromethyl ketone (made as in Example 4), 0.35 g. of sodamide and 1.9 g. of 2-bromo-1-diethylaminooethane in 100 ml. of benzene is heated at reflux for six hours. The reaction mixture is treated with water and the separated organic layer is extracted with dilute hydrochloric acid. The acid extracts are neutralized with dilute sodium bicarbonate solution and extracted with benzene. The solvent is removed in vacuo to give residual 10-[3'-(N-β-diethylaminoethoxyethylpiperazinyl)-propyl]-2-phenothiazinyl trifluoromethyl ketone.

Example 20

A mixture of 29.3 g. of 2-phenothiazinyl trifluoromethyl ketone (prepared as in Example 1), 14.9 g. of 3-chloro-1-diethylaminopropane and 3.7 g. of sodium amide in 150 ml. of dry xylene is refluxed for three hours. Working up the cooled reaction mixture as in Example 2, yields 10-(3'-diethylaminopropyl)-2-phenothiazinyl trifluoromethyl ketone.

The free base is readily converted to the hydrochloride salt by treatment with anhydrous hydrogen chloride in ether solution.

Example 21

A mixture of 4.2 g. of 10-(3'-piperazinylpropyl)-2-phenothiazinyl trifluoromethyl ketone (prepared as in Example 4), 1.8 g. of 1-iodobutane and 1.4 g. of potassium carbonate in 100 ml. of toluene is stirred and heated at reflux for four hours. The reaction mixture is filtered and the filtrate washed with water, dried and concentrated. The residue is dissolved in ethyl acetate and treated with two equivalents of maleic acid to give the dimaleate salt of 10-[3'-(N-butylpiperazinyl)-propyl]-2-phenothiazinyl trifluoromethyl ketone.

Example 22

A suspension of 4.2 g. of 10-(3'-piperazinylpropyl)-2-phenothiazinyl trifluoromethyl ketone (prepared as in Example 4), 2.3 g. of 4-bromo-4'-hydroxybutyl ether (prepared by the careful treatment of 4,4'-dihydroxybutyl ether with one equivalent of hydrobromic acid) and 1.4 g. of potassium carbonate in 150 ml. of xylene is refluxed for ten hours. Treating the reaction mixture as described in Example 17 yields 10-[3'-(N-hydroxybutoxybutylpiperazinyl)-propyl]-2-phenothiazinyl trifluoromethyl ketone.

A solution of 5.6 g. of the free base in 75 ml. of benzene is treated with 2.0 ml. of butyryl chloride. After standing at room temperature for 12 hours, the reaction mixture is poured into water, neutralized with dilute sodium bicarbonate solution and extracted with benzene. Evaporation of the solvent leaves a residue which is dissolved in alcohol and reacted with anhydrous hydrogen chloride gas, thus yielding the dihydrochloride of 10-[3'-(N-butyryloxybutylpiperazinyl)-propyl]-2-phenothiazinyl trifluoromethyl ketone.

What is claimed is:

1. Chemical compounds of the class consisting of a free base and its nontoxic organic and inorganic acid salts, the free base having the formula:

in which A is an alkylene chain having 2 to 6 carbon atoms, separating the nitrogens to which it is attached

by at least 2 carbon atoms; and Z is a member selected from the group consisting of dialkylamino, pyrrolidinyl, piperidinyl, morpholinyl, thiomorpholinyl, piperazinyl, N-alkylpiperazinyl, N-(ω-hydroxyalkylene)-piperazinyl,

5 N-(ω-alkanoyloxyalkylene)-piperazinyl, N-(ω-hydroxyalkyleneoxyalkylene)-piperazinyl, N-(ω-alkanoyloxyalkyleneoxyalkylene)-piperazinyl, N-(ω-benzyloxyalkylene)-piperazinyl, N-phenylalkylpiperazinyl, N-diethylaminoethylpiperazinyl, N-acetyl piperazinyl and N-benzyloxyalkylene-piperazinyl; each of the aforesaid alkyl moieties having 1 to 4 carbon atoms; each of the aforesaid alkylene moieties having 2 to 4 carbon atoms; and each of the aforesaid alkanoyl moieties having 2 to 4 carbon atoms.

2. Chemical compounds having the formula:

in which A is an alkylene chain having 2 to 6 carbon atoms, separating the nitrogens to which it is attached by at least 2 carbon atoms; and the alkyl moieties have 1 to 4 carbon atoms.

3. A chemical compound having the formula:

4. Chemical compounds having the formula:

in which A is an alkylene chain having 2 to 6 carbon atoms, separating the nitrogens to which it is attached by at least 2 carbon atoms; and the alkyl moiety has 1 to 4 carbon atoms.

5. A chemical compound having the formula:

6. Chemical compounds having the formula:

in which the alkylene moiety has 2 to 4 carbon atoms.

7. A chemical compound having the formula:

11

8. Chemical compounds having the formula:

in which the alkylene moiety has 2 to 4 carbon atoms; and the alkanoyl moiety has 2 to 4 carbon atoms.

9. A chemical compound having the formula:

10. Chemical compounds having the formula:

12

in which each of the alkylene moieties has 2 to 4 carbon atoms.

11. A chemical compound having the formula:

5

12. 2-phenothiazinyl trifluoromethyl ketone.
